CLAIM

The ornamental design for a sock, as shown and described.

DESCRIPTION

FIG. 1 is a perspective view of a sock in accordance with a first embodiment of our design;

FIG. 2 is a side view (e.g., right side) of the sock in accordance with FIG. 1, with the other side (e.g., left side) being a mirror image thereof;

FIG. 3 is a top view of the sock in accordance with FIG. 1; FIG. 4 is a top view of the sock in accordance with FIG. 1, the top view presenting a two-dimensional view of the design;

FIG. 5 is a perspective view of a sock in accordance with a second embodiment of our design;

FIG. 6 is a side view (e.g., right side) of the sock in accordance with FIG. 5, with the other side (e.g., left side) being a mirror image thereof;

FIG. 7 is a top view of the sock in accordance with FIG. 5; FIG. 8 is a view of the sock in accordance with FIG. 5, the top view presenting a two-dimensional view of the design; FIG. 9 is a perspective view of a sock in accordance with a third embodiment of our design;

FIG. 10 is a side view (e.g., right side) of the sock in accordance with FIG. 9, with the other side (e.g., left side) being a mirror image thereof;

FIG. 11 is a plan view of the sock in accordance with FIG. 9; and,

FIG. 12 is a top view of the sock in accordance with FIG. 9, the top view presenting a two-dimensional view of the design.

The broken lines show portions of the sock that form no part of the claimed design.

(Continued)

The areas of contrasting appearance may be associated with different colors, different materials or combinations of materials, different stitching or other sock property.
